Louis M. Sanders ATTORNEYS.

UNITED STATES PATENT OFFICE.

JAMES T. SIBLEY, OF NEWARK, NEW JERSEY.

AUTOMATIC STOP FOR PHONOGRAPH-MOTORS.

1,325,119.

Specification of Letters Patent. Patented Dec. 16, 1919.

Application filed August 17, 1917. Serial No. 186,865.

To all whom it may concern:

Be it known that I, JAMES T. SIBLEY, a citizen of the United States, residing in the city of Newark, county of Essex, and State 5 of New Jersey, have invented a new and useful Improvement in Automatic Stops for Phonograph-Motors, set forth in the following specification.

In my prior application, Ser. No. 179,365, 10 filed July 9th, 1917, I have illustrated and described an improved stop device, which serves to break the circuit, whenever the tone arm is swung clear of the record and released, so as to cut off the power of the 15 electric motor which drives the turntable. My present improvement embodies all of the essential features of said application, and has in addition thereto, means for stopping the motor by cutting off the current supply 20 to the motor upon the completion of the record. Since the record groove varies in length, and terminates nearer the center, for the longer records, it is necessary to provide means for adjusting the point at which 25 the circuit is broken, so that when and only when the record has been entirely completed, the circuit shall be broken and the motor consequently stopped.

The particular form of motor to which 30 my present improvement is specifically adapted is illustrated in my prior application, Ser. No. 175,565, filed June 19th, 1917.

The mechanism which I employ to accomplish this result is illustrated in the accompanying drawing and described in the following specification.

Figure 1, is a plan view of so much of a tone arm as is necessary to show my improvement connected therewith.

Fig. 2, is a vertical section on line 2—2 of Fig. 1.

Fig. 3, is a rear elevation of the tone arm showing my adjustable circuit breaker in place.

Fig. 4, is a plan view of a part of the circuit breaker detached.

Fig. 5, is a section on line 5—5 of Fig. 3.

Fig. 6, is a fractional front view of the base of the tone arm.

Fig. 7 illustrates the tonearm.

Similar reference numerals refer to like parts throughout the specification and drawing:

The fixed base 1, of the tone arm is secured 55 to the phonograph cabinet by the screws 2, in the usual manner, through the flange 3. The

base 1, is provided with the two circumferential grooves 4, 5, upon its inner face, which serve as raceways for the balls 6, 7. The cap socket 8, having the two apertures 9, 60 10, is provided in the outer side of the base for the introduction of the balls into the raceways, and the cap 11, held in place by the screws 12, prevents the escape of the 65 balls.

The swinging tonearm 13, is in all respects like the tonearm of my prior application, Ser. No. 179,365, except for the connection with the base 1. The vertical end of the tone-arm 13, is reduced as at 14, for insertion into the base 1, and is provided with the circumferential grooves 15, 16, which register with the grooves 4, 5, and receive the balls 6, 7. When coupled together, with the balls in their respective raceways and the 75 cap 11, secured in place, the tone-arm 13, is locked to the base 1, but free to swing in a horizontal plane, with a minimum of resistance.

Extending through diametrical apertures 80 17, 18, in the tone-arm is the rod 19, the outer end of which is supported by and slides in the apertured bracket 19', upon the under side of the tonearm; I have deemed it unnecessary to describe it further than to say 85 that it reciprocates in the apertures 17, 18, under the influence of the spring 20, upon raising the pivoted sound box section 13' of the tone-arm, and thereby withdrawing the arm 51 from engagement with the end 90 of the rod 19. Upon the end of the rod 19, I secure the downwardly projecting contact pin 21, by means of the adjustable connecting piece 22. Rigidly secured to the base 1, but insulated therefrom, is the metal 95 connecting strip 23, bent into the arc of a circle concentric with the said base. Upon the strip 23, I mount the sliding connector 24, providing the same with a groove to fit the strip 23. In order to provide a 100 comparatively firm frictional engagement between the strip 23, and connector 24, I secure to the connector 24, the spring metal strap 25, by means of the screws 26, through the lateral projections 27. The strap is 105 extended, as shown, to form the handle 28, by which the connector may be manually operated; the other end of the strap is cambered, as at 29, to bear upon the face of the strip 23, in order to offer frictional resistance to the movement of the connector 24. When properly adjusted, the strip 23, and

65

105

110

connector 24, are in position for contact with the downwardly projecting pin 21, and upon the normal swinging of the tone-arm 13, during the playing of a record, this contact is maintained by the action of the spring 20.

Upon the upper part of the connector 24, is the inclined cam 30, the higher portion of which is made up of an insert of insulation, as 31. Adjacent to the highest point of the cam is the projection 32, through which extends an adjusting screw 33, having an insulating point 34, in position to engage the pin 21, as it rides upon the cam 30 and the insert 31.

The connector 24, is provided with an extension 35, upon the free end of which the insulating stud 35' is secured, in the path of the pin 21.

20 In order that the pin 21, may be free from contact with the extension 35, when said pin is at any point between the cam 30, and the stud 35', I insert a small stop pin 36, in the adjustable connecting piece 22, to engage the side of the tone-arm 13, so that while the spring 20, insures contact between the pin 21, and the connector 24, or the strip 23, yet such contact is broken at some interval before the pin can reach the stud 35'.

In Fig. 1, I have shown a simple wiring diagram to include the pin 21, and connector strip 23. The motor is indicated at 37, and the battery or other electric source, at 38. The strip 23, is connected by the wire 39, through the battery 38, thence to the motor 37 from which a wire 40 leads to the base 1, which in turn is connected by the wire 41, to the rod 19.

40 I prefer to lead the wire 41 to the rod 19, rather than to ground it alone upon the base 1, for the reason that the balls 6, 7, do not form a good path for the current. In practice, I have found the balls scarred 45 by electrolysis, when they are utilized as a part of the circuit, with a consequent deterioration of the bearing.

The circuit is completed whenever the pin 21, bears upon the metal of the strip 23, or the connector 24, but is broken when said pin rides upon the insulating insert 31.

In practice, the tone-arm 13, is swung to the extreme right, to insure engagement of the pin 21, with the stud 35' and consequent movement of the connector 24, to its extreme left hand position upon the strip 23. The tone-arm is then moved to the left until the stylus needle of the sound box upon the tone-arm is immediately above the innermost record groove. In this movement, the pin 21, will ride up on the cam 30, and its insert 31, until it engages the insulating point 34, of the screw 33. Further movement of the arm 13, will move 65 the connector 24 upon the strip 23, so that

when the stylus is at the inner record groove, the pin 21, will have properly adjusted the connector 24, upon the strip 23. The tone-arm and sound box may then be adjusted to playing position and when the stylus needle is lowered upon the record, the spring 20, will bring the pin 21, in proper contact with the connector 24, and strip 23. When the stylus needle has traversed the record to its innermost groove, the pin 21, will have ridden upon the cam 30, to and upon the insulating insert 31, which of course will break the electric circuit through the motor, and consequently stop it.

It is understood that when the tone-arm 13, is swung to the extreme right and the free sectional end thereof released and drops below the record, the rod 19, will be moved endwise by contact with the arm 51 to carry the pin 21, free from contact with the connector 24, and strip 23. This operation however is fully described in my above named prior application, and forms no part of my present application.

With my present improvement in connection with the motor of my prior application Ser. No. 175,565, no other stopping or starting mechanism is necessary or desirable, since the motor is started by placing the sound box in playing position upon the record, and it automatically stops either at the completion of the record or upon swinging the tone-arm to the extreme right and releasing the sound box, as described in application Ser. No. 179,365.

It is obvious that many changes in proportion or dimensions of parts may be made without departing from the spirit and scope of my improvement.

The adjusting screw 33, may be set so as to permit the phonograph turntable to rotate by its own momentum to carry the soundbox stylus over two, three or even more of the last record grooves, independent of the motor, and after the circuit has been broken, this will be readily understood from a reference to my motor application Ser. No. 175,565, above referred to.

I claim:

1. In a stop device for phonograph motors, the combination of a swinging tone-arm, of a contact pin yieldingly mounted upon said tone-arm, a fixed contact strip mounted for normal engagement with said pin, means for separating said pin from said strip at each end of the swing of said tone-arm, a motor in circuit with said pin and strip, and a source of electrical supply in said circuit.

2. In a stop device for phonograph motors, the combination of a swinging tone-arm, and a rigid support therefor, with a contact pin upon said tone-arm, a contact strip secured upon but insulated from said support and in normal engagement with said pin, and adjustable means upon said strip for breaking

- said engagement at any predetermined point in the swing of said tone-arm.
3. In a stop device for phonograph motors, the combination of a swinging tone-arm and a support therefor, with a contact strip upon but insulated from said support, a contact pin upon said tone-arm for normal engagement with said strip, a sliding connector upon said strip, said connector having means thereon for engagement with said pin at each end of the swing of said tone-arm to adjust the position of said connector upon said strip.
4. In a stop device for phonograph motors, the combination of a contact strip, a moving contact pin carried by the phonograph tone arm in normal sliding engagement with said strip, and means for breaking said engagement at any predetermined point, comprising a connector slidably mounted upon said strip whereby the position of said connector upon said strip may be adjusted, said connector having insulating projections at each end thereof in the path of and for engagement with said moving pin, and a cam upon said connector adjacent to one of said projections for lifting said pin free from said strip.
5. In a phonograph stop device, the combi-

nation of a swinging tone-arm and the support therefor, a contact strip upon but insulated from said support, a contact pin upon said tone-arm for sliding engagement with said strip, and an adjustable insulating cam upon said strip for breaking said engagement at a predetermined point.

6. In a phonograph stop device, the combination of a swinging tone-arm and a fixed support therefor, a contact strip upon but insulated from said support, a contact pin upon said tone-arm for sliding engagement with said strip, and means carried by said strip for breaking said engagement at any predetermined point.

7. In a phonograph stop device, the combination of a swinging tone-arm and a fixed support therefor, a contact strip mounted upon said support, a contact pin upon said tone-arm for sliding engagement with said strip, a sliding connector upon said strip having stop projections thereon in the path of and for engagement with said pin at each end of the swing of said tone-arm to adjust said connector upon said strip, and a cam upon said connector in the path of said pin to engage the same and break the engagement of said pin with said strip.

JAMES T. SIBLEY.
